UNITED STATES PATENT OFFICE.

GEORG SCHMIDBAUER, OF MUNICH, AND JULIUS ERNST, OF REGENSBURG,
GERMANY.

THROTTLE-VALVE.

SPECIFICATION forming part of Letters Patent No. 670,737, dated March 26, 1901.

Application filed November 9, 1900. Serial No. 35,979. (No model.)

To all whom it may concern:

Be it known that we, GEORG SCHMIDBAUER, residing at Munich, and JULIUS ERNST, residing at Regensburg, Germany, subjects of the 5 King of Bavaria, have invented certain new and useful Improvements in Throttle-Valves, of which the following is a full, clear, and exact description.

The present invention relates to that class 10 of valves which are controlled by the pressure of the fluid within them and are automatically closed on a sudden decrease of such pressure.

The valves may be used in connection with 15 any fluid-pressure, such as steam, gas, or air, and the invention comprises the details of construction hereinafter set forth, and particularly pointed out in the claims.

Referring to the accompanying drawings, 20 in which the letters of reference indicate similar parts in the several views, Figure 1 is a sectional elevation showing our improved valve located in the steam-dome of a boiler, certain parts being shown in plan. Fig. 2 is 25 a vertical section of the valve-casing, the dependent guide-rod being shown in plan. Fig. 3 is a plan view of the valve. Fig. 4 is a vertical section of the valve. Fig. 5 is a horizontal section on the line 5 5, showing the 30 construction of the bifurcated lever and connected parts.

In the present case the valve is shown built 35 in the dome of a boiler; but it will be readily understood that a separate housing could be formed around the valve, which could then be mounted in any pipe system, in the open air, or in any other desirable manner.

The steam-valve A is mounted on the dome 40 in the usual manner, and within the dome a bend a is attached, having its upper end in communication with the valve-housing on the outside. The lower end of the bend carries the valve-seat support or casing b, having the valve-seat i secured at its lower edge and 45 a spider b', supporting a central sleeve i', in which the downwardly-extending spindle or guide-rod c is rigidly attached by means of the shoulder and upper nut, as will be seen

at Fig. 2. On this spindle c the valve slides up and down. The said valve is composed of 50 the following parts: the cup d, preferably made of copper-plate, for the sake of lightness, the sleeve f, mounted centrally therein and arranged to slide on the spindle c, and the upper guide-plate or spider g, fitting into 55 the top of the cup slightly below the rim of the same and having a central ring to fit onto the shoulder formed in the upper part of the sleeve f, Fig. 4. The cup e is held up against the shoulder e', formed at the lower end of the 60 sleeve, by means of a nut e. The lower end of the spindle c is turned down to form a shoulder c', against which an arm k, extending upwardly, is held up by means of the nut c', said arm or support k serving as the fulcrum of a bent lever l, having its horizontal arm bifurcated to embrace the spindle c and its lower arm bent horizontally to carry a weight m, adjustable thereon. The cup d rests on the bifurcations o and is carried thereby. 70 The weight m is adjusted to allow the valve to remain open when the proper pressure is on both sides of the same—*i. e.*, when the pressure in the dome of the boiler and in the pipe beyond the valve A is equal. As soon as the 75 pressure outside the valve A or d g drops suddenly—for instance, in the case of a pipe bursting or from any other disorder—the pressure in the dome will immediately force the valve d g up against its seat and prevent the 80 further escape of steam through the passage a. In order to open the valve when starting, it will be necessary to establish equal pressure on both sides of the same, and this is effected by means of a by-pass consisting of a small 85 pipe n, leading from the dome into the housing of the valve A on the steam side of the same.

In order to properly tighten up the valve d g on its spindle, a gland h is provided, 90 which is screw-threaded to the spindle c and on which the sleeve f of the valve slides. As already stated, the weight m acts as a counterpoise to keep the valve open when the pressure is the same at both sides of the same, 95 and since the valve is of a very light con-

struction the weight need not be very large and may easily be adjusted on the arm of the lever *l*.

We claim as our invention—

- 5 1. The combination in a pressure-regulator, of a valve-casing having a guide-rod secured thereto, a valve arranged to slide on said rod, a lever fulcrumed on said rod and having one extremity engaging said valve, and a counterbalancing-weight mounted on said lever, said casing also having a by-pass around the valve.
- 15 2. The combination in a pressure-regulator, of a valve-casing having a vertically-arranged guide-rod secured thereto, a valve arranged to slide on said rod, a lever fulcrumed on said rod and having one extremity engaging said valve, and a counterbalancing-weight mounted on said lever, said casing also having a constricted by-pass around the valve.
- 25 3. The combination in a pressure-regulator, of a valve-casing having a vertically-arranged guide-rod secured thereto, a valve arranged to slide on said rod, a lever fulcrumed on said rod, said lever having one extremity bifurcated and having said bifurcation partly surrounding said guide-rod and also engaging said valve, and a counterbalancing-weight mounted on said lever, said casing also having a by-pass around the valve.
- 30 4. The combination in a pressure-regulator, of a valve-casing having a vertically-arranged guide-rod extending downwardly therefrom, a cup-valve arranged to slide on said guide-rod, an arm secured to said rod, a lever fulcrumed to said arm, said lever having one extremity bifurcated and having said bifurcation partly surrounding said rod and also engaging said cup-valve, and a counterbalancing-weight mounted on said lever.
- 35

bifurcation partly surrounding said rod and also engaging said cup-valve, a counterbalancing-weight mounted on said lever, said casing also having a by-pass around the valve.

5. The combination in a pressure-regulator, of a valve-casing having a guide-rod secured thereto, a valve arranged to slide on said rod, a lever fulcrumed on said rod and having one extremity engaging said valve, and counterbalancing-weight mounted on said lever.

6. The combination in a pressure-regulator, of a valve-casing having a vertically-arranged guide-rod secured thereto, a valve arranged to slide on said rod, a lever fulcrumed on said rod, said lever having one extremity bifurcated and having said bifurcation partly surrounding said guide-rod and also engaging said valve, and a counterbalancing-weight mounted on said lever.

7. The combination in a pressure-regulator, of a valve-casing having a vertically-arranged guide-rod extending downwardly therefrom, a cup-valve arranged to slide on said guide-rod, an arm secured to said rod, a lever fulcrumed to said arm, said lever having one extremity bifurcated and having said bifurcation partly surrounding said rod and also engaging said cup-valve, and a counterbalancing-weight mounted on said lever.

In witness whereof we have hereunto set our hands in presence of two witnesses.

GEORG SCHMIDBAUER.
JULIUS ERNST.
